UNITED STATES PATENT OFFICE.

JULIUS A. SPENCER, OF DWIGHT, ILLINOIS.

BALING-PRESS.

SPECIFICATION forming part of Letters Patent No. 278,371, dated May 29, 1883.

Application filed February 20, 1883. (No model.)

To all whom it may concern:

Be it known that I, JULIUS A. SPENCER, of Dwight, in Livingston county, and State of Illinois, have invented certain new and useful 5 Improvements in Baling-Presses, the construction and operation of which I will proceed to explain, reference being had to the annexed drawings and the letters and figures thereon, in which—

10 Figure 1 is a plan view on the top; Fig. 2, a horizontal central sectional view through the plunger and feed-door; Fig. 3, a perspective view on the side of the baling-chamber, and Fig. 4 a side elevation.

15 This invention relates to certain improvements in that class of baling-presses known as "horizontal" or "procumbent" baling-presses and is an improvement on the press for which Letters Patent dated August 22, 1882, No. 262,992, were issued to this applicant.

20 The first in order of the improvements in this machine is in the device for reciprocating the plunger P'. The rear of the plunger P' is hinged to the end of the toggle-joint, consisting of the two levers P and P², jointed together about two-thirds the way back from the plunger. The rear end of the lever P² is hinged to the frame A at S. A chain, c', attaches to the joint J of the toggle, and extends 25 upward and attaches at its upper end to the beam B, supported by the beams B' and B³. The drive-chain c, which comes from the power and passes over the pulley R, and runs horizontally forward, is provided at that end with the pulley-block R', that travels on the chain c'. When the power is applied to the chain c it will pull on chain c' and carry it backward, by means of which the toggle-joint P and P² is carried upward and draws the 30 plunger P' back out of the bale-chamber, and all the parts, when the plunger is back, are in the position shown by the dotted lines in Fig. 4.

35 It will be seen that the joint S, where the rear end of the toggle hinges, is on a plane below the center of the plunger P'. When the parts are in the position shown in Fig. 4, the plunger is forward at its farthest point against the bale in the bale-chamber, and the 40 toggle-joint lies so the joint J is depressed to

a line a little below the points where the lever P is hinged to the plunger, and S, where lever P² is hinged to the frame, and the joint J rests on the post J'. When in such position chain c' is nearly straight, and when chain c begins to pull on it, it will pull upward on the toggle-joint with great force to raise the joint above its center, when the elasticity of the bale will start the plunger back rapidly and throw the toggle-joint up, so the 55 plunger will move back at a greater speed than the chain c travels.

60 In the operation of baling or pressing the hay into bales the plunger P' is driven forward into the bale-chamber against the material to be baled by means of the chain m, which comes from the power over pulley n, and attaches to the under side of the knee-joint of the toggle P P², as shown in Fig. 4. When the power pulls on said chain m the knee-joint is straightened, and thereby presses the plunger P' forward, as shown in said figure. The power by means of which chains c and 65 m are operated may be so constructed that it pulls alternately on said chains, but not on both at the same time. Chain m is used to pull down on the knee or toggle joint to throw the plunger forward, while chains c and c' are for the purpose of returning the plunger by lifting up on the knee or toggle joint to which 70 chain c' attaches, as before stated.

75 Any power may be used that will pull alternately on chains m and c, and as the power is no part of this invention, no further description of it is deemed to be necessary.

80 It is obvious that as the lever P² approaches a perpendicular line it opens the toggle-joint easier, until at last its own weight carries the plunger back as far as is necessary, as shown by the dotted lines in Fig. 4.

85 Hinging the toggle-joint on the frame at S on a plane below the center of the plunger P', where its opposite end is hinged, partially relieves the plunger from friction on the bottom of the bale-chamber, when the chain m pulls 90 the toggle-joint down to force the plunger forward, as the tendency of the toggle so arranged is to force the plunger more directly forward without frictional contact with any side of the bale-chamber to any extent. Another object 95 100

in so hinging the toggle at S, as stated, is that when the roof of the bale-chamber is loosened the force of the plunger against the bale will raise the bale a little off the floor, so that when the plunger recedes from the bale it is loose and can be readily removed from the bale-chamber.

Another improvement consists in the means for opening the feed-door D at the side of the feed-chamber when the plunger returns. This is accomplished in the following manner: An arm, L, is pivoted at its lower end in the frame A, as shown in Fig. 4. To its upper is attached the cord w', which passes over the pulley R' in the outer end of the beam v', and passes thence down and attaches to the weight a², which slides up and down in the ways a³a³. When the toggle moves upward and backward the pin o at the joint J (shown more clearly in Fig. 1) comes in contact with the arm L and carries it backward between the beams v v until it is in the position shown by the dotted lines in Fig. 4, which will elevate the weight a², so the turned-up or bent end of the rod a will fall into the notch on the side of the weight a², (shown at b in Fig. 3.) This slackens the cord w, which connects the weight a² with the latch e on the side of the door D, so the said door may be closed by the operator. Said door remains closed until the plunger is moved forward to press the bale, and far enough so the bale is carried past the door D, when the pin p on the side of the plunger meets the opposite bent end of the rod a, as shown by the dotted lines in Fig. 3, bearing it down and releasing the other end from the

notch in the weight a², which permits the weight a² to fall, and, by means of its attachment with the door D by the cord w, pulls back the latch e and pulls the door D open, thus saving the labor of having to open it by hand. The dotted lines in Fig. 2 show the position of the door D when open. The rod a has an arm, a', attached to its side next the weight a², to cause its bent end b to bear against the weight a², so as to readily fall into the notch of the weight.

Having thus described my invention, what I claim as new, and desire to secure by Letters Patent, is as follows, to wit:

1. The combination of the toggle-joint P P², vertical chain c', and drive-chain c, having the pulley R' to roll on chain c', all adapted to operate as and for the purpose set forth.

2. The combination of the vertical arm L, pivoted at the lower end in the frame A, cord w', weight a², having a notch in its side for the reception of the bent rod a, bent rod a, having its inner end bent to engage with the trip-pin p on the plunger P' and its outer end bent to fall in the notch of the weight a², pin p, and cord w, all adapted to operate as and for the purpose set forth.

3. In a baling-press, the toggle-joint P and P², having its opposite end from the plunger hinged to the frame A on a plane below the point of its attachment to the plunger, as and for the purpose set forth.

JULIUS A. SPENCER.
